UNITED STATES PATENT OFFICE

LE ROI E. HUTCHINGS, OF BUFFALO, NEW YORK, ASSIGNOR, BY MESNE ASSIGNMENTS,
TO REMINGTON RAND INC., OF NEW YORK, N. Y., A CORPORATION OF DELAWARE

INDEX DEVICE

Application filed August 24, 1926. Serial No. 131,187.

This invention relates to index devices and has reference more particularly to index devices of the vertical visible type such as that shown in my co-pending application, Serial No. 105,289.

An object of this invention is to provide a tray construction which will be simple to operate and durable over a long period of time.

Another object of my invention is to provide an end construction for a tray of the type above mentioned which will be inexpensive to manufacture; also to improve index devices in other respects hereinafter specified and claimed.

15 Reference is to be had to the accompanying drawings forming a part of this specification, in which,

Fig. 1 is a perspective view of my improved index devices,

20 Fig. 2 is a transverse sectional elevation through the device,

Fig. 3 is a fragmentary corner elevation showing the swinging support arrangement,

25 Fig. 4 is a vertical, sectional, fragmentary view through one of the frames supporting the separator cards,

Fig. 5 is a vertical sectional elevation showing the improved catch mechanism on the line 5—5 of Fig. 3,

30 Fig. 6 is a plan view showing the swinging support,

Fig. 7 is a fragmentary perspective view showing the tray construction at the connection for the swinging support,

35 Fig. 8 is a perspective view of the follower member, and,

Fig. 9 is a perspective view of the spring used in connection with the follower member.

Referring to the drawings by numerals, 40 10 indicates the bottom of the file tray, which has upstanding sides 11 and 12 along each longitudinal edge thereof. End members 13 are formed by upwardly extending sections on the members of the bottom 10, the ends

45 13 being considerably less in height than the side 11. Adjacent the inner junction of the bottom 10 with the side 12, a U-shaped member 14 is secured inside the tray in any suitable way such as by spot welding. The up- 50 per leg 15 of the channel 14 is narrower than

the bottom leg 16 of said channel and forms a channel with the bottom 10 for the reception of frame bearings 17.

A similar U-shaped channel 18 is secured to the inside of the tray at the inner junction of bottom 10 and side 11. The upper leg 19 of the channel 18 is narrower than the lower leg 20 of said channel and said lower leg may be secured to the bottom 10 by spot welding. The channel leg 19 is considerably wider than the channel leg 15 and is also adapted to serve as a rail for the reception of frame bearings 21.

In order to resiliently and detachably maintain the bearings 17 and 21 under their respective rails 15 and 19, I provide a U-shaped follower member 22 of suitable width, 55 that the legs of same will be slidably received between the legs 19 and 20 of the channel 18. The legs of the channel 22 are 60 preferably turned outwardly and a flat spring 23 of wave-like shape is positioned in the space formed by the channels 22 and 18 so that said spring normally tends to move the channel 22 to the left as seen in Fig. 2 65 against the ends of bearings 21.

The bearings 17 and 21 are cylindrical in shape and are secured to the ends of a sheet metal roll 24 formed on the bottom of a frame member 25. The construction of the frame member 25 has been explained in the description of the device shown in Figs. 1 to 14 of the above mentioned application. Its structure includes an inwardly turned flange 26 along each vertical edge of said frame, being adapted to engage the ends of separator rails 27 so as to maintain said rails in abutting position edge to edge. One edge of a separator card 28 is secured to rail 27 in any suitable way such as by staples, (not shown), 80 and the bend line 29 for said separator card is formed by a series of perforations 30. A transparent sheath 31 is attached by pasting or other means to the upper edge of each separator card 28 and said separator card preferably has cut-away portion 32 under the sheath 31 adapted to permit the indicia 33 on the upper edge of record cards 34 to be visible through said transparent sheaths. It 85 is thus seen that the separator cards 28 form a 90

100

Referring to the drawings by numerals, 40 10 indicates the bottom of the file tray, which has upstanding sides 11 and 12 along each longitudinal edge thereof. End members 13 are formed by upwardly extending sections on the members of the bottom 10, the ends

45 13 being considerably less in height than the side 11. Adjacent the inner junction of the bottom 10 with the side 12, a U-shaped member 14 is secured inside the tray in any suitable way such as by spot welding. The up- 50 per leg 15 of the channel 14 is narrower than

series of vertical pockets for receiving the record cards 34. The frame members 25 are so held by their bearings 17 and 21, that they are pivotally connected to the bottom 10 5 of the tray, thus permitting them to be tilted back and forth at an angle to the vertical. I provide a hinged end wall or end member 35 on each end of the tray 10 for supporting the frames 25 in vertical or inclined position, 10 a hinge 36 being formed at the bottom of said hinged end wall 35 said hinge cooperating with hinge 37 formed on the upper edge of end walls 13 to pivotally connect said hinged walls 35 to said end walls 13. Any 15 suitable way may be used to detachably maintain the hinged end walls 35 in vertical position as shown in Fig. 3 or in inclined position as shown in Fig. 1.

In the preferred embodiment of my invention, this hinged end wall supporting arrangement consist of a U-shaped swinging member 38 having legs 39 terminating at their free ends in inwardly extending pivot hooks 40. The hooks are adapted to engage 20 under the corner of a U-shaped stiffening wire 41 formed around the ends and tops of the side walls 11. The metal of the side wall 11 is preferably formed into an inwardly extending pivot bearing 42 adapted to pivotally 25 receive the hooks 40.

The swinging members 38 are of slightly greater width than the hinged end walls 35 so that said hinge frames are received between the legs 39. Slide bearings 43 are preferably attached to the outer surface of hinged end walls 35 such as by rivets 44. The slide bearings 43 have stop shoulders 45 which are adapted to engage the swinging member 38 in its lowermost position so as to limit the outward movement of the hinged end wall 35. It will be seen in Fig. 1 that the entire structure is very rigid since the swinging member 38 and its arms 39 form a continuous reinforcement with wire 41 around the upper 40 45 edge of the tray when the hinged end walls 35 are tilted outwardly to permit reference to the record cards 34.

In the top of each hinged end wall 35 I preferably provide an opening 46 having a smooth surface at its top formed by a roll 47 being formed at the upper edge of the hinged end wall 35. A similar roll 48 is formed at the bottom of the hand opening 46 and a hinge wire or rod 49 passes through 50 55 the roll 48. Intermediate its ends, the roll 48 is cut away so that a catch 50 having a hinge bearing 51 may be pivotally mounted on the rod 49. The catch 50 is in the form of a lever having its upper arm 52 extending into the hand opening 46 in convenient position for manual actuation. The lower arm 53 of the catch 50 is formed into a hook 54 adapted to receive the swinging arm 38 when same is in substantially vertical position, that 60 65 is when the hinged end wall 35 is in vertical

position or in closed position of the filing device. A cam surface 55 is formed on the bottom of the hook 54 so that when the swinging member 38 moves upwardly in the slide bearings or guides 43, said swinging member 38 engages said cam surface 55 and swings the catch 50 outwardly, the latter then dropping by gravity again to a vertical position with the hook 54 under the swinging member 38. 70 75

In operation, or when the filing device is in open position as shown in Fig. 1 the frames 25 may be tilted at will about the vertical position on bearings 17 and 21 so that record cards 34 in the pockets formed by separator cards 28, may be referred to or removed from the pockets. In this open position hooks 40 of swinging member 38 engage wires 41 at the bearings 42 and hold the hinged end walls 35 in inclined position so as to limit the 80 85 tilting of the hinge frames 25. When it is desired to close the file, the hinged end walls 35 are moved upwardly into vertical position, which causes the cam surface 55 on catch 50 to engage the swinging member 38, thus causing the catch 50 to swing outwardly and then hook under swinging member 38 so as to rigidly support the hinged end walls 35 in vertical or closed position. The entire filing device may now be carried from place to place by gripping the hand openings 46. 90 95

I would state in conclusion that while the illustrated example constitutes a preferred embodiment of my invention, I do not limit myself precisely to the details herein described, since manifestly the same can be considerably varied without departing from the spirit of the invention as defined in the appended claims. 100 105

I claim:

1. In a filing device, a tray having bottom and side members, end members pivoted at each end of said tray, a plurality of frame members pivotally mounted on said bottom member parallel to and between said end members, a swing member pivotally mounted on and extending across the ends of said side members at each end of said tray, bearing means on said end members for slidably receiving portions of said swing member for limited movement, said swing members adapted to limit the pivotal movement of said end members and to cooperate therewith to limit the movement of the frame members between said end members, and a manually releasable catch mounted on each end member and adapted to engage said swing member at one end of its movement in said bearing means and lock both said end member and said swing member against pivotal movement. 110 115 120

2. In a filing device, a tray having bottom and side members, end members pivoted at each end of said tray, a plurality of frame members pivotally mounted on said bottom 125 130

member parallel to and between said end members, a swing member pivotally mounted on and extending across the ends of said side members at each end of said tray, bearing means on said end members for slidably receiving portions of said swing member for limited movement, said swing members adapted to limit the pivotal movement of said end members and to cooperate therewith to limit the movement of the frame members between said end members and a manually releasable catch pivotally mounted on each end member and having a cam surface adapted to automatically engage said swing member at one end of its movement in said bearing means, and lock both said end member and said swing member against pivotal movement.

3. In a filing device, a tray having a base and upstanding side members, end members pivotally connected to each end of said tray, a plurality of frame members pivotally mounted on said base parallel to said end members and extending therebetween, a swing member at each end of said tray, each swing member having hook portions pivotally connected to a respective end of each side member, bearing means on each end member for slidably receiving portions of its adjacent swing member, a shoulder portion on said bearing means engageable by its respective swinging member to limit the outward pivotal movement of said end member relative said tray, and means on each end member for automatically engaging said swing member to lock the same against movement when said end member is in a substantially vertical position relative said base, said end members when locked being adapted to maintain said frame members against pivotal movement in a substantially vertical position relative said base; and when said end members are pivoted to their outward positions, said frame members being adapted for limited pivotal movement therebetween.

4. In a filing device, a tray having a base and upstanding side members, end members pivotally connected to each end of said tray, a plurality of frame members pivotally mounted on said base parallel to said end members, a swing member at each end of said tray, each swing member having hook portions pivotally connected to a respective end of each side member, bearing means on each end member for slidably receiving portions of its adjacent swing member, and catch means on each end member adapted to engage its swing member to lock the same against movement when said end member is in a substantially vertical position to said base, said end members when locked being adapted to maintain said frame members against pivotal movement in a substantially vertical position relative to said base.

5. In a filing device, a tray having a base

and upstanding side walls, said side walls having a reinforcing rod along the free edges thereof, a bearing portion at each end of each side wall enclosed by said reinforcing rod, an end member pivoted at each end of said tray, a swing member extending across each end of said side walls and pivotally connected in said bearing portions, a slide bearing on each end member for slidably receiving portions of said swing member, for limited movement therein, each swing member being adapted to limit the pivotal movement of the adjacent end member.

6. A filing device, comprising a tray having a bottom, upstanding side walls, and relatively lower upstanding end walls, an end member hinged on each end wall, a plurality of record bearing frame members pivotally mounted on said bottom parallel to said end walls, a catch on each end member, means mounted across respective ends of said side walls each adapted to engage the catch on its adjacent end member to lock said end member in a predetermined position relative its respective end wall, both end members when locked maintaining said frame members within the confines of said tray in immovable position, both end members when their respective catches are released being pivotally movable to a position angular to and exterior of the confines of said tray.
